Patented June 3, 1969

214,329

SNOW SLED

Loran R. Hill, Olney, Ill., assignor to American Machine
& Foundry Company, a corporation of New Jersey

Filed June 13, 1968, Ser. No. 12,341

Term of patent 14 years

Int. Cl. D12—13; D21—02
U.S. Cl. D34—15

FIG. 1

FIG. 2

FIG. 1 is a perspective view of the snow sled when viewed from the top front of the sled; and

FIG. 2 is a perspective view of the sled when viewed from the bottom rear of the sled.

I claim:

The ornamental design for a snow sled, substantially as shown.
